BRUSH AND HANDLE ASSEMBLY

Harry W. Stephenson, Santa Monica, and
Ben D. Hall, Los Angeles, Calif.

Application December 17, 1946, Serial No. 716,840

2 Claims. (Cl. 15—185)

1

The present invention relates to brushes of the type which may be carried conveniently in traveling and which may be converted into a compact sanitary package.

An object of the present invention is to provide an improved brush structure characterized by its compactness and small size to which it may be reduced when it is desired to carry the assembly either on the person or in traveling luggage.

Another object of the present invention is to provide an improved brush structure wherein the brush bristles themselves are moved relative to one another in order to minimize space requirements to provide a relatively large structure in use and to break up the possible accumulation of foreign matter between adjacent bristles.

Yet another object of the present invention is to provide improved brush structures characterized by their simplicity, inexpensiveness, ease with which they may be manufactured through mass production methods and expediency and of pleasing appearance.

Still another object of the present invention is to provide a brush assembly wherein a covering therefor may be converted into a suitable handle for the brush assembly, or vice versa.

Still a further object of the present invention is to provide a brush assembly in which the wearable parts thereof may be conveniently cleaned and replaced.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is an end view of the brush assembly incorporating the present invention when conditioned for use.

Figure 2 is an end elevation corresponding to Figure 1 when the brush assembly is conditioned for nonuse and for convenient portability.

Figure 3 is a view taken substantially in the direction taken by the line 3—3 in Figure 2.

Figure 4 is a perspective view of another brush assembly incorporating the present invention when conditioned for use.

Figure 5 is a sectional view taken substantially on the line 5—5 of Figure 4.

Figure 5A shows some of the parts of Figure 5 in enlarged form.

Figure 6 is a sectional view taken substantially on the line 6—6 of Figure 4.

2

Figure 7 is a sectional view corresponding to the view in Figure 5 but with the combined cover and handle member therefor in an intermediate position between its closed and open positions.

Figure 8 is a perspective view of a portion of the combined cover and handle member for the brush assembly of Figure 4 but with a spring member dismounted therefrom.

Figure 9 is a perspective view of the brush assembly shown in Figure 4 when the brush bristles are covered and the assembly is conditioned for convenient, compact portability, the assembly being shown in its inverted position.

The brush assemblies shown in Figures 1 and 15 4 have certain features in common among which resides the structure whereby adjacent rows of brush bristles may be moved with respect to one another and whereby a portion of the assembly may be alternately used either as a cover member 20 or as a handle for the brush bristles.

In the brush assembly shown in Figures 1 through 3, rows of brush bristles 10, 11, 12 and 13 have one of their ends embedded respectively in plastic rectangularly shaped strips 14, 15, 16 and 17 through which flexible canvas-like material 18 extends. The flexible material 18 serves to maintain the strips 14, 15, 16 and 17 in spaced relationship to one another and yet to allow relative movement therebetween when and as the combination handle and cover members 19 and 20 are moved between their extreme positions shown in Figures 1 and 2. The flexible canvas-like material 18 is not only bonded to the plastic strips 14, 15, 16 and 17 but also to the members 19 and 20 through which they centrally extend. Although we prefer to use plastic material, other materials may be used, for example, wood, ebony, composition materials and the like. Further, adjacent strips may be hinged by small connecting metallic hinges.

The assembly may be maintained in the positions shown in Figures 1 and 2 by means of any one of a number of conventional type releasable fastening means 22 arranged to releasably maintain adjacent free ends of the members 19 and 20 together. Such fastening means of course may take different forms and shapes and is shown herein for purposes of simplicity as a pivoted hook member 23 arranged to cooperatively engage a suitable post 24 on the other member 19 or 20, as the case may be.

The abutting adjacent ends of members 14, 15, 16, 17, 19 and 20 are shaped so that adjacent members solidly abut one another in the extreme positions shown in Figures 1 and 2 whereby the

brush assembly is relatively solid when used or carried, even though it is flexible in positions intermediate to those shown in Figures 1 and 2, such adjacent sides of members 14, 15, 16, 17, 19 and 20 being tapered as shown to provide different desirable results.

It is apparent that each row of brush bristles 10, 11, 12 and 13 either may comprise a single continuous row of bristles or, as preferred herein, each row is discontinuous in nature comprising spaced tufts of bristles. These bristles preferably are imbedded in plastic material to which they, as well as the flexible material 18, are readily bonded in the manufacturing process, the plastic material being preferably translucent or opaque.

Although we have shown only four rows of bristles 10, 11, 12 and 13, it is obvious that one skilled in the art with the teachings and structure incorporated herein may make brush assemblies incorporating more or less than four such rows.

It is apparent that the combined handle and cover members 19 and 20 may take different forms and shapes to provide a convenient hand grip when the assembly is intended for use; for example, matched portions 21 for insertion of fingers may be provided.

In the other arrangements shown in Figures 4 to 9, inclusive, individual rows of brush bristles 30, 31, 32, 33 and 34 are automatically moved from a retracted position to a useful position when the combined cover and handle member 36 is moved from its closed position shown in Figure 9 to its open position shown in Figure 4, each row of bristles 30 to 34, inclusive, being mounted for independent rotational movement with respect to one another on corresponding rotatable shafts 38, 39, 40, 41 and 42, each of which has centrally located gear teeth 44 on the other side thereof arranged to cooperate with a spring-biased rack member 45 arranged to be engaged and moved by the combined cover and handle member 36 to thereby cause corresponding movement of rotatable shafts 38, 39, 40, 41 and 42.

The rack member 45 as perhaps best seen in Figure 6 is U-shaped in cross section, being formed of sheet metal material and arranged to slide in a guideway 46 which is a centrally located aperture in the U-shaped sheet metal member 47, upon which opposite ends of rotatable members 38 through 42 are journaled. This U-shaped member 45 is normally biased to the right in Figure 5 by one or more compression type springs 48 disposed between the wall of the housing 49 and the rack member 45 to normally press its end 50 out of an opening 51 in the other end of the housing 49 in a position where the end 50 may be engaged by the member 36 which is pivotally mounted on the housing 49. Outward movement of the member 50 is limited by engagement of the enlarged portion 55 on the rack member 45, the outward movement of the rack member 45 being limited by engagement of the enlarged portion 55 contacting the inner surface of the housing member 49. Member 47 forms only a part of the bearing for the members 38, 39, 40, 41 and 42 and the other part of the bearings for such members is provided by the pair of opposed bent edges 58 and 59 of the housing member 49.

The combined cover and handle member 36 is pivotally mounted on the housing member 49 at one end thereof by means of a pin 60 which passes through suitably turned apertured portions 63 of the housing member 49 aligned with

a pair of spaced turned apertured portions 61 and 62 on member 36.

Pin 60 has an enlarged square cross sectional portion 65 disposed between turned bearing members 61 and 62 which cooperates with the free end of leaf spring member 66 having its other end fastened by rivets 68 or the like to the member 36, or for cooperation with the edge 67 of member 36 to thereby firmly maintain the member 36 in place as the pair of folding sides 70 and 71 are folded inwardly as shown in Figure 4 wherein such edges 67 cooperate with the square cross sectional portion 65. These side portions 70 and 71 are pivotally mounted on the central portion 72 by the conventional type of hinge 73 whereby the member 36 may be conveniently reduced in size to simultaneously lock the member 36 in place and to decrease its size so that it forms a suitable handle of pleasing appearance.

In operation of the brush assembly described in connection with Figures 4 through 9 the assembly shown in Figure 9 in its closed condition is converted into the assembly shown in Figure 4 by pivoting the member 36 about the pin 60 through an angle of 180° to cause the spring member 66 to resiliently engage the square cross sectional portion 65 of the pin 60 thereby to maintain the member 36 in position while the pivoted side members 70 and 71 and the edges 67 engage the square enlarged cross sectional portion 65 thereby to maintain the member 36 firmly in position as shown in Figure 5. Upon pivotal movement of the member 36 from its position shown in Figure 9 to its position shown in Figure 4 the end 50 of the rack member 45 is pressed inwardly against the action of compression spring 48 as shown in Figure 7 thereby to rotate each and every one of the brush bristles 30 through 34 from the retracted horizontal position in Figure 7 to a substantially vertical position wherein such brush bristles are more useful in brushing operations performed by a person grasping the handle 36.

In order to restore the assembly from its open position shown in Figure 4 to its closed position shown in Figure 9, it is necessary to pivot the flap members 70 and 71 away from one another to the position shown in Figure 8 thereby to cause disengagement of the edges 67 from the square cross sectional portion 65. Thereafter the entire member 36 is pivoted on its pivot pin 60 through an angle of 180° to its relative position shown in Figure 9, thereby allowing the compression spring 48 to automatically move each and every one of the rows of brush bristles 30 to 34, inclusive, to retracted position, the cover member 36 being maintained closed by engagement of leaf spring 66 with pin portion 65.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

We claim:

1. In a brush assembly, a plurality of base members, a row of bristles mounted on each base member, a pair of combination handle and cover members, a flexible member passing through and bonded to said base members and said combination handle and cover members, whereby said last members may be swung to one position to

provide a handle and to another position to cover said bristles, and means for selectively locking the free ends of said pair of members in either of said positions.

2. In a brush assembly, a plurality of base members, a row of bristles mounted on each base member, a pair of combination handle and cover members, and a flexible member passing through and bonded to said base members and said combination handles and cover members, said base members and said combination handle and cover members having tapered edges, whereby said last members may be swung to one position to provide a handle and to another position to cover said bristles.

HARRY W. STEPHENSON.
